ATTORNEY

UNITED STATES PATENT OFFICE

140,135

DESIGN FOR A PRINTING TELEGRAPH CABINET

Walter J. Zenner, Des Plaines, Ill., assignor to
Teletype Corporation, Chicago, Ill., a corpora-
tion of Delaware

Application June 22, 1944, Serial No. 114,128

Term of patent 14 years

(Cl. D64—11)

To all whom it may concern:

Be it known that I, Walter J. Zenner, a citizen of the United States, residing at Des Plaines, in the county of Cook and State of Illinois, have invented a new, original, and ornamental Design for a Printing Telegraph Cabinet, of which the following is a specification, reference being had to the accompanying drawing, forming a part thereof.

Fig. 1 is a perspective view of a recording telegraph cabinet showing my new design, and

Fig. 2 is a side elevational view of the upper part of the cabinet shown in Fig. 1.

The rear wall of the cabinet is substantially flat except that the upper portion thereof is curved forwardly, merging with the top of the cabinet as indicated in the figures.

I claim:

The ornamental design for a printing telegraph cabinet, substantially as shown and described.

WALTER J. ZENNER.
